UNITED STATES PATENT OFFICE.

JOHN P. DUGAN, OF BALTIMORE, MARYLAND, AND CHARLES O. DUGAN, JR., OF PHILADELPHIA, PENNSYLVANIA, ASSIGNEES TO THE DUGAN SEAL COMPANY, OF BALTIMORE, MARYLAND, A CORPORATION OF MARYLAND.

SEAL.

Application filed April 23, 1923. Serial No. 634,192.

To all whom it may concern:

Be it known that I, JOHN P. DUGAN, a citizen of the United States of America, residing in the city of Baltimore, State of Maryland, and I, CHARLES O. DUGAN, Jr., a citizen of the United States of America, residing in the city of Philadelphia, State of Pennsylvania, have invented certain new and useful Improvements in Seals, of which

10 the following is a specification.

The seal which is the subject of this invention may be applied to baggage, shipping tags, express packages and tags, freight packages, freight car doors, packages of val-

15 uables, and other packages, safes and the like. In fact, it may be used in any connection as indicating means to show whether any closure has been tampered with.

The device consists of a plurality of discs 20 which are centrally apertured and secured together with the apertures in registration. One of the discs is recessed as to the face, which contacts the other disc, the recess being diametrically placed, in that it crosses 25 the center, and being relatively deep near the center and shallow at the ends.

Situated in the recess which is closed by the other disc or two thin, steel plates, in the nature of plate springs. These plates meet 30 or almost meet in the center where they are free and are secured to the discs at their outer ends, preferably by the securing means which holds the discs together. A piece of relatively soft wire is secured at one end 35 between the discs, the other end being free. This wire is preferably somewhere from 6" to 10" long.

To close the seal, the free end is passed through or about the parts to be sealed and 40 then is thrust through the central opening in the rear or unrecessed disc and between the adjacent ends of the plates, forcing them apart and backward to the bottom of the recess, till sufficient opening is formed to pass 45 the end of the wire. In this position the end of the wire referred to as the free end is fastened and can not be removed without breaking the wire or making it clearly apparent that the seal has been tampered with, 50 for the ends of the plates which are preferably sharpened bite into the wire and prevent its withdrawal in the direction from which it was inserted, having, under these

circumstances, a toggle action, tending to hold the wire more tightly the greater the 55 tension applied, so that with an excessive pull the wire is cut off or broken instead of being released from the plates. It will be apparent that the wire or flexible binding member, being of uniform cross-section, as 60 shown, may be locked at any point in its length, making the loop thus formed capable of being taken up or drawn up to meet any conditions which may be presented, making the seal capable of universal application to baggage, freight car doors and 65 other doors.

If desired, the end of the wire may be hardened to make breakage thereof more certain when there is tampering with the 70 seal. Under such circumstances, detection is, of course, easy on account of the variation in length of the wire, the condition of the end and the loss of the part which was thus hardened.

75 Preferably, we provide prongs of tin or similar material for securing the seal to a tag or check, with the center opening of the seal or disc in registration with the eye of the check or tag. A portion of the check may, 80 to advantage, be allotted to the seal to be left on the seal until the package reaches the owner, the check having other portions separated by perforated lines for use of the baggage department of the railroad, one, 85 in accordance with the usual practice, being the passenger's duplicate.

In the accompanying drawing:—

We have illustrated a seal constructed in accordance with our invention in the preferred form.

In the drawings:—

Fig. 1 is a front elevation of the seal applied to a check, the side referred to as the front side being the side from which the 95 end of the wire is inserted in seal.

Fig. 2 is an elevation taken from the right of the seal as seen in Fig. 1.

Fig. 3 is a section on the line 3—3 of Fig. 1 looking from the right.

Fig. 4 is a section on line 5—5, Fig. 3 looking to the right, showing the right hand disc and the gripping plates.

Fig. 5 is a sectional elevation on the line 5—5 of Fig. 3, looking to the left in that 105 figure, showing the pronged member and

the flat disc in side elevation, the rivets or pins which hold the disc or plate springs being in section.

Referring to the drawings by numerals:
 5 The seal, as shown, consists of two discs, 1 and 2, which may be of leather, fibre or any suitable substitute, as metal or wood. These members, 1 and 2, are referred to as discs, for convenience in describing the invention, but their shape except as herein-after described, is not of any particular importance though the circular or disc seal might be considered the most acceptable as to appearance and convenience of production.

10 These discs 1 and 2, are pierced, forming the holes, 3 and 4, so placed as to be in registration, when the discs are secured together with their edges in alignment, and 15 preferably centrally located. For further convenience, the disc, 1, will be referred to as the front disc, and the disc, 2, as the rear disc. The rear disc is recessed at 5, the recess extending across the disc so that the 20 hole, 4, is centrally placed as to said recess. In other words, the recess, 5, in the form of the invention shown, is a channel or groove extending diametrically across the disc on the face thereof, and is deeper at the center 25 than at the ends adjacent the periphery of the disc. This recess, 5, which is covered by the front disc, contains the locking plates, 6. These are two in number, each being in 30 length equal to about one-half the length of 35 the recess, 5, which, in this instance, means that they are equal in length to one-half the diameter of the discs. These plates, 6, which may, to advantage, be of plate spring material, are seated in the recess, 5, which is 40 preferably just wide enough to receive them and are secured at their outer ends to the discs or between the discs, and are free at their inner ends, 7, which substantially meet and which are preferably sharpened to engage 45 the wire or other flexible binding member, 8, to be described. In the present instance, the discs are held by pins or rivets, 10, by means of which the discs are secured together, as aforesaid, the disc, 1, covering 50 the recessed face of the disc, 2, in which the plates, 6, are seated, the disc, 1, serving to close the recess and cover the plates, preventing displacement thereof and protecting them so that they can not be tampered with 55 without making evident the fact that this has been done.

The wire, 8, referred to, is shown as secured at one end, 12, between the discs, the securing means in the form of the invention 60 shown, including a circular depression, 13, in the inner face of the rear disc, 2, in the flat face thereof at one side of the recess, 5. The end, 12, of the wire, is bent in the form of a loop which is situated in said depression and there is a channel, 14, in the face

of the disc, leading from the depression, 13, to the periphery of the disc. If desired, a pin, 15, may be passed through the looped end, 12, and through the discs, or any other suitable means for permanently fastening one end of the wire, 8, to the seal body may be used. The wire, 8, is of any suitable length and is led from the depression through said channel.

As shown, it is 8" to 9" long, but this is immaterial, and the end portion, 16, which may be referred to as the free end, i. e. the end opposite to the end, 12, which is permanently fastened to the seal, may, to advantage, be hardened to cause it to break in case of an attempt to pull out the locked end, giving clear evidence of such tampering.

15 The device, as shown, further includes means for fastening a tag or check to the seal, though this is not regarded as an essential feature of the invention in its broader scope.

20 As shown, this means consists of a plurality of prongs of thin sheet metal which may, to advantage, be of what is known commercially as tin. The prongs are in the form of a cross, 17, centrally apertured at 18, to register with the apertures 3-4 in the disc. This cross, 17, is seated between the discs, preferably in the shallow crossed grooves, 19, in the back face of the front disc, 1. As shown, this cross is also held by the rivets, 10.

25 In operation, the wire, 8, is passed through or around the members which are to be sealed together, the object of the seal, as aforesaid, being to give evidence of tampering with any package or thing thus sealed, or rather to show when it has not been tampered with, meaning that the package, 100 when opened, has not been interfered with by any outside agency since it was sealed.

30 The free end, 16, the wire having been, as aforesaid, passed through, in or around the members to be sealed together, is then thrust through the opening, 3, in the front disc, passing between the adjacent edges, 7, of the plates, 6, and then out through the opening 4, in the rear disk, 2.

35 It will be noted that the wire or flexible binding member 8 is of uniform cross-section throughout and without shoulders or particular points of attachment, and that any part of the wire may be fastened to the seal by drawing the wire through the seal and adjusting the size of the loop, making it possible to adapt the seal to any situation or circumstance presented.

40 The wire is intended to be thrust forward or inward so far that the edges, 7, 125 will contact with the soft portion of the wire and not with the hardened end, 16. But hardening is not essential.

45 Any attempt to withdraw the end, 16, from the seal, i. e. to pull it back, will 130

cause the edges, 7, to bite into the surface of the wire, the plates having a toggle action in relation thereto, which causes the edges, 7, to engage with the greater pressure, the greater the tendency to withdraw the wire, so that it can not, in fact, be pulled out without breaking or disrupting any of the parts.

We have shown in Figure 1, in connection with the seal, a check, 20, consisting of a passenger's duplicate, 21, and baggage check, 22, and a seal stub, 23, the latter being secured to the seal and being intended to go to the recipient of the baggage to indicate to him that the baggage has not been opened since the seal was applied in the presence of the sender.

We have thus described specifically and in detail a single embodiment of our invention in order that the nature and operation of the same may be clearly understood, however, the specific terms used herein are used descriptively rather than in a limiting sense, the scope of the invention being defined in the claims.

What we claim and desire to secure by Letters Patent is:

1. A seal consisting of a plurality of members secured together face to face forming a seal body, said members having registering holes and one of said members having a recess which is intersected intermediately by said holes, plates seated in said recess having free, substantially contacting edges, substantially in line with said holes, a flexible metal binding member of uniform cross-section having one end permanently secured to the seal, the other end being adapted to be passed through said holes, and between 40 and in contact with the edges of said plates, the plates being flexibly mounted to converge toward said edges, and having a toggle action and the edges having a biting action on the wire, when tension tending 45 to withdraw it from the seal is applied to the wire.

2. A seal consisting of a plurality of members secured together face to face forming a seal body, said members having substantially aligned holes and one of said members having a recess which is intersected intermediately by said holes, plates in said recess having free, substantially contacting edges, adjacent to said holes, portions of said plates remote from the contacting edges being flexibly connected to the seal body, a flexible metal binding member of uniform cross-section and without lateral projection having one end permanently secured to the seal body, the other end being adapted to be passed through said holes, and between and in contact with the edges, said edges having a biting action on the wire when tension tending to withdraw 65 it from the holes is applied, to the wire and

prongs adapted to engage a card projecting from the seal body.

3. A combination check and seal consisting of a card, a seal body secured to said card, a metal wire of uniform cross-section 70 having one end secured to the seal body member, the other end of the wire being free, locking means comprising plates arranged toggle-wise, the remote ends secured to the body and the edges of said plates being substantially in contact, the body member having a hole in alignment with said edges, so that the free end of the wire can be thrust through said aperture and between 75 said plates and locked at any point in its length by the toggle action forming a loop which can be reduced to the desired extent by drawing the wire through the seal.

4. A combination check and seal consisting of a card, a seal body member secured 80 to the card, a flexible metal binding member of uniform cross-section having one end secured to the seal body member, the other end being free, locking means comprising converging members arranged toggle-wise 85 with the remote ends connected to the body and adjacent edges substantially in contact, the body member having holes in alignment with said edges, so that the free end of the binding member can be thrust through said aperture and between 90 said converging members and locked at any point by the toggle action, the body member having a closed aperture for said converging members, providing play for said edges. 100

5. A seal comprising a continuous flexible metal binding member of substantially uniform cross-section, a seal body to which said member is permanently secured at one end, the seal body having walls enclosing a chamber, said chamber having substantially aligned openings by way of which openings the free end of said binding member may be passed through the seal body forming a loop, and a hard metal jaw having a sharp gripping edge, the edge being normally between said openings, the jaw being inclined away from one of said openings and having a slight degree of play, and means opposite said jaw for preventing the flexible member from yielding away from the gripping edge, the inclined jaw having a toggle action and serving to lock the binding member automatically at any point in its length, permitting the slack 110 to be taken up by drawing the free end through the seal. 115

Signed by us at Baltimore, Maryland, this 23rd day of April, 1923.
